CLAIM

The ornamental design for a lighting fixture, as shown and described.

DESCRIPTION

FIG. 1 is a front perspective view from below of a lighting fixture according to the new design;

FIG. 2 is a rear perspective view from above thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top view thereof;

FIG. 8 is a bottom view thereof;

FIG. 9 is a front perspective view from below thereof, but shown illuminated;

FIG. 10 is a rear perspective view from above thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top view thereof; and,

FIG. 16 is a bottom view thereof.

The broken lines in the drawings illustrate portions of the environment and the lighting fixture and form no part of the claimed design.

The stippling shown in FIGS. 9-11 and 13-16 is solely for the purpose of illustrating the appearance of illumination and does not represent texture or surface ornamentation.
